HANDLE FOR SUCTION CLEANERS

Frank S. Howard, Chicago, Ill., assignor to Birtman Electric Company, a corporation of Illinois

Application January 15, 1945, Serial No. 572,834

7 Claims. (Cl. 306—12)

1

This invention relates to an improved handle for suction cleaners and relates particularly to such a handle that can be easily positioned at a number of elevations from the floor.

In the floor type suction cleaner which has the usual cleaner body and attached handle for propelling the cleaner around the room, it has been found necessary to construct the handle so that it can be placed in one position and be held there unsupported by the operator. These handles in the past have been oftentimes bulky and the means for holding them in position have not been entirely satisfactory. In this invention, I have provided an improved handle structure that is light in weight and that can very easily be adjusted to any one of a number of given positions by merely turning the handle around its central axis. Thus, when the handle is in one position and it is desired to change it to another, the operator of the cleaner merely turns the handle a short way in either direction and the catch on the bottom of the handle is released and can then be moved to a new position.

The invention will be described as related to the embodiment shown in the accompanying drawings.

Of the drawings, Fig. 1 is an elevation, partially broken away, of the standard floor type of cleaner and the new handle; Fig. 2 is a section taken along line 2—2 of Fig. 1; Fig. 3 is a section taken along line 3—3 of Fig. 2; Fig. 4 is a section taken along line 4—4 of Fig. 2.

In the drawings, there is shown a suction cleaner 10, the new handle 11 attached thereto, and a dust bag 12. The dust bag and the handle are attached to the cleaner in the usual positions. The new handle, which is the subject of this invention, is the usual tubular structure having a circular cross section at its lower end, as is found in most cleaners of this type. At the bottom of the handle, where it joins on to the cleaner, is located a surrounding reinforcement 13. This reinforcement is held by two pivot bars 14 arranged in line with each other and in a horizontal position so that the handle 11 can be turned about this pivot in a substantially vertical plane. The reinforcement 13 also contains a set screw 15 which extends into the handle and around which is located an oval slot lying transverse to the length of the handle. This set screw 15 and oval

2

slot 16 are provided so that the handle may be turned around its central axis for a short distance. The locking mechanism whereby the handle structure is locked in one of any given positions comprises an arcuate plate 17 mounted in the cleaner beyond the bottom of the handle, with the plate lying in an arcuate plane substantially at right angles to the vertical plane of movement of the handle 11. This plate has a radius of curvature that is substantially centered at the pivot of the handle. The plane of curvature of the plate is substantially within the plane of movement of the handle. On the edge of the plate 17, there are provided a number of notches 18. These notches are engaged by an extension piece 19, which is normally held in notch-engaging position by means of a coil spring 19. In order to provide for removing the extension from any given notch, there is located at the bottom 20 of the handle structure an auxiliary piece 20 extending from the extension 18 to the bottom of the handle 11. This auxiliary piece is held in position within the reinforcement 13. The end of the auxiliary piece, which contacts the handle 11, has a rounded surface 21 which engages a rounded notch at the bottom of the handle.

In the structure described above, the extension 18 on the bottom of the handle structure may be removed from engagement with any given notch by merely turning the handle 11. This turning causes the auxiliary piece 20 to be moved out of engagement with the notch on the bottom of the handle and thereby is pushed forward. The forward movement causes the extension to move out of engagement with its notch and the handle may thereupon be moved to a different position for engagement with another notch. As soon as the handle is in position with this second notch on the arcuate plate 17, the handle is turned back to its original position and the extension thereupon engages a new notch. In order to assist in properly locating the handle, there is provided a ball 23 in the handle reinforcement 13 and this ball presses against a small hole 25 that is located in the handle 11. The ball is held in engagement with this hole by means of a spring 24. Thus, as soon as the handle is turned to its normal position, the ball 23, under the urging of spring 24, rolls into the hole 25 and locks the handle in its correct position.

The description of the operation of the new handle 11, given hereinabove, is for removing the extension 18 from a notch 29 in order to lower the handle from an upper position to a lower one. When moving the handle from horizontal position, to operating position, and on up to vertical position, there is no need to turn the handle about its axis as the extension piece 18 slides over the notches 29. This is arranged for by providing the notches with gradually sloped surfaces on the receding or lower ends to present no definite stop when moving the handle from a lower to a higher position. The stop surfaces of the notches are positioned so as to prevent the handle from falling from a higher to a lower position only.

This new handle structure has an electric cord 26 running through its center to connect with the motor in the cleaner. In order to avoid undue wear on the cord by raising and lowering the handle, the bottom end of the handle structure 27 is provided with generally rounded edge portions 27 in the shape of a bell. By means of this structure, sharp bending of the cord is avoided.

In the suction cleaner described herein the handle 11 extends into the cleaner body 10 and is pivotally mounted thereon by pivot members arranged in line on opposite sides of the cleaner body. These pivot members may have the form of round bars 14 extending from the outer surface of the cleaner body into the handle reinforcement 13 and are preferably threaded on their outer ends so that they can be screwed into the cleaner body and thus held in position. Because of this construction it is now no longer necessary to provide an outer covering for the pivot members as they have a pleasing effect on the eye and do not need to be covered. This elimination of outer covering makes the cleaner lighter in weight as well as cheaper to construct, and it is easier to remove the handle for repair work if such becomes necessary.

When it is desired to use the cleaner under very low structures such as beds or the like, the handle of the cleaner may be moved to a horizontal position. This is done by releasing the notch-engaging extension piece 18 in the manner described above. The handle is then lowered to its horizontal position and is supported by a rest 28. In this position, the extension piece 18 does not engage any of the notches, but merely rests on a curved portion 30 of the handle structure.

Having described my invention in considerable detail, as exemplified by one embodiment of the same, it is to be understood that I am not limited by these details unless otherwise specified, but rather it is my intention that the invention be construed broadly within its spirit and scope, as set out in the accompanying claims.

I claim:

1. A handle structure for a suction cleaner or the like capable of being easily adjusted to one of a number of given positions in a substantially vertical plane comprising a handle extending into the cleaner, a pivot within the cleaner about which the handle may be turned, a generally arcuate fixed plate mounted in the cleaner and beyond the bottom end of the handle with the center of its radius of curvature substantially coinciding with the center of pivot of the handle, a plurality of notches in the arcuate plate, a movable extension piece on the bottom of said handle structure extending outwardly normally to engage one of said notches and hold the handle in a given position, and means for disengaging the

movable extension piece from its engaged notch by turning the handle about its central axis.

2. A handle structure for a suction cleaner or the like capable of being easily adjusted to one of a number of given positions in a substantially vertical plane comprising a handle extending into the cleaner, a pivot within the cleaner about which the handle may be turned, a generally arcuate fixed plate mounted in the cleaner and beyond the bottom of the handle with said plate lying substantially within the vertical plane of movement of the handle and with the radius of curvature of the plate centered substantially at the pivot of the handle, a plurality of notches in the arcuate plate, a movable extension piece on the bottom of said handle structure extending beyond the handle normally to engage one of said notches and hold the handle in a given position, an auxiliary piece on the bottom of the handle adjacent the extension piece, and means for changing the position of the auxiliary piece in order to press against the said movable extension and disengage it from its notch.

3. A handle structure for a suction cleaner or the like capable of being easily adjusted to one of a number of given positions in a substantially vertical plane comprising a handle extending into the cleaner and capable of being turned from side to side about its central axis, a pivot within the cleaner about which the handle may be turned, a generally arcuate plate mounted in the cleaner and beyond the bottom of the handle with said plate lying substantially within the vertical plane of movement of the handle and with the radius of curvature of the plate centered substantially at the pivot of the handle, a plurality of notches in the arcuate plate, an extension piece on the bottom of said handle structure extending beyond the handle normally to engage one of said notches and hold the handle in a given position, an auxiliary piece on the bottom of the handle adjacent the extension piece, and means for changing the position of the auxiliary piece by turning the handle about its central axis in order to press the auxiliary piece against the said extension and disengage it from its notch.

4. A handle structure for a suction cleaner or the like capable of being easily adjusted to one of a number of given positions in a substantially vertical plane comprising a handle extending into the cleaner and capable of being turned from side to side about its central axis, a pivot within the cleaner about which the handle may be turned, a generally arcuate plate mounted in the cleaner and beyond the bottom of the handle with said plate lying in an arcuate plane substantially at right angles to the vertical plane of movement of the handle and with the radius of curvature of the plate centered substantially at the pivot of the handle, a plurality of notches in one edge of said plate, an extension piece on the bottom of said handle structure extending beyond the handle normally to engage one of said notches and hold the handle in a given position, an auxiliary piece on the bottom of the handle adjacent the extension piece, and means for changing the position of the auxiliary piece by turning the handle about its central axis in order to press the auxiliary piece against the said extension and disengage it from its notch.

5. A handle structure for a suction cleaner as set out in claim 4 wherein there is provided a spring on said extension piece normally holding said extension piece in notch-engaging position.

6. A handle structure for a suction cleaner as

set out in claim 4 wherein said auxiliary piece is slidably held by a bottom reinforcement in said handle structure and extends from the said extension to the bottom of the handle, and a notch in the bottom of the handle engaging the handle end of said auxiliary piece.

7. A handle structure for a suction cleaner or the like capable of being adjusted to one of a number of given positions around a pivot near the bottom of the handle wherein said handle 10 is hollow with an electric cord running down through the interior thereof to the cleaner and the handle structure is flared outwardly on two opposite sides of the cord from a point near the pivot to the bottom of the handle to avoid bend- 15

ing the cord sharply when the handle structure is moved from position to position in substantially the plane of the outward flares.
